TOILET BOWL

Willis B. Cramer, Perrysville, Ohio, assignor to Mansfield Sanitary Pottery, Inc., Perrysville,
Ohio, a corporation of Ohio

Application November 15, 1951, Serial No. 17,426

Term of patent 14 years

(Cl. D4—5)

To all whom it may concern:

Be it known, that I, Willis B. Cramer, a citizen of the United States, residing at Perrysville, in the county of Ashland and the State of Ohio, have invented a new, original, and ornamental Design for a Toilet Bowl, as shown in the accompanying drawing, wherein:

Fig. 1 is a side elevational view of a toilet bowl, showing my new design;

Fig. 2 is a front end elevational view of the design illustrated in Fig. 1;

Fig. 3 is a top plan view of the design illustrated in Fig. 1;

Fig. 4 is a rear end elevational view of the design illustrated in Fig. 1; and

Fig. 5 is a bottom plan view thereof.

I claim:

The ornamental design for a toilet bowl, substantially as shown.

WILLIS B. CRAMER.
